APPARATUS FOR STACKING ARTICLES

William E. Keller, West Warren, Mass., assignor to Associated Engineers Inc., Springfield, Mass., a corporation of Massachusetts

Application October 23, 1948, Serial No. 56,100

3 Claims. (Cl. 214—6)

1

This invention relates to improvements in apparatus for stacking articles.

The principal objects of the invention are directed to the provision of an apparatus for arranging successive articles in a stack and for transporting the stack away from a stacking position.

The apparatus of the invention is adapted for stacking various and sundry articles but for purposes of disclosure the novel features of the invention will be described in connection with the stacking of cartons in their non-set-up relation.

According to novel features of the apparatus successive cartons are arranged in a stack and successive stacks are transported to a discharge position by a means which allows the stacking operation to continue during the transporting operation.

That is, a transporter is movable between stacking and discharge positions and cartons are stacked on or over the transporter in its stacking position while when the transporter is moving from and returning to its stacking position cartons are being stacked in the stacking position thereof so as to provide the basis of a successive stack. In this way high speed operation is attained.

Various counting devices may be employed to provide stacks of desired predetermined count and the stacks may be transported in various directions from the stacking position.

With the foregoing and various other novel features and advantages and other objects of my invention as will become more apparent as the description proceeds, the invention consists in certain novel features of construction and in the combination and arrangement of parts as will be hereinafter more particularly pointed out in the claims hereunto annexed and more fully described and referred to in connection with the accompanying drawings wherein:

Fig. 1 is a longitudinal sectional elevational view through the stacking apparatus embodying the novel features of the invention;

Fig. 2 is a transverse sectional elevational view through the apparatus on the line 2—2 of Fig. 1;

Fig. 3 is a plan view of the transporter of the apparatus; and

Fig. 4 is a sectional elevational view on the line 4—4 of Fig. 3.

Referring now to the drawings more in detail, the invention will be fully described.

Upper and lower longitudinal members 2 and 4 at opposite sides of the machine are secured together and to uprights 6, 8, and 10.

Transverse members 12, 14 and 16 are secured to the members 2 and 4 whereby a strong, rigid support is provided.

Transverse members 18 and 20 are suitably secured to the support and longitudinally extending transversely spaced ways 22 have op-

posite ends secured to the said members 18 and 20.

A transporter includes a slide 24 which is slid- able on the ways 22 between a stacking position, shown in Fig. 1, and a discharge position forwardly and to the right thereof. Pushers 26 preferably in the form of tubes have their lower ends secured to the slide and they extend upwardly therefrom.

Stack supports 28 which extend longitudinally are spaced apart transversely and have their opposite ends secured to blocks 30 fixed to the members 18 and 20.

Rear guides 32 in the form of inverted U's have outer side portions 34 fixed to a transverse member 36 and inner portions fixed to the members 28. The transverse member 36 has side portions 40 secured to the support.

Side walls 42 are provided and are mounted for movements toward and away from one another. Forward and rear transverse bars 44 have outer supporting portions 46 which carry foot portions 48 that are secured to the support.

Sleeves 50 are slidably adjustable on the bars 44 and brackets 52 are secured to and connect the side walls 42 and sleeves 50.

A forward stop or guide plate 54 is secured to rods 56 extending transversely from a bracket 58. The bracket 58 embraces a wall 42 so as to be slidable therealong and is held in adjusted position by any suitable means such as set screws 60 carried by the bracket and engageable with the wall. The transverse width of plate 54 is less than the distance between adjacent inner sides of members 26 so that as the transporter moves forwardly the members 26 pass opposite sides of member 54.

Longitudinal ledges 60' are provided on the walls 42 for supporting opposite ends of the cartons.

For purposes of disclosure it will be assumed that successive articles such as cartons are fed from the left in Fig. 1 and over member 32 so that they drop onto the supports 28. The side walls will be adjusted to accommodate the cartons and the parts 38 of said members 32 will align the cartons to provide a stack thereof. That is the forward end of the cartons will strike plate 54 and fall downwardly.

The stack is moved to the right or forwardly to discharge position by movement of the transporter, the members 26 pushing the stack along the supports 28.

The stack may be discharged onto any means but for illustrative purposes a conveyor is shown which includes an endless apron 66 supported by a rotatable roll 68.

The transporter may be operated by any suitable means but for purposes of disclosure the following is provided.

A shaft 70 is rotatable in bearing means 72

and has fixed thereto a gear 74 and a cable drum 76. Cable means includes a run 78 having an end fixed to the transporter at 80 extends over a sheave 82 and to and around the drum 76. Runs 86 of cable extend upwardly through the pushers and have lower ends thereof connected to eyes 88 which are associated with caps 90 at the lower ends of the pushers, see Fig. 4. These runs 86 pass over rotatable sheaves 92 and 94 and to and around the drum 76.

The cable is so arranged that as the drum is rotated in opposite directions the transporter is moved back and forth between its stacking and discharge positions.

As the transporter is moved to discharge position the pusher members 26 assume the position represented by dot-dash lines 26' and the cable runs assume the position shown by dot-dash lines 86'. Thus, during back and forth movements of the transporter incoming cartons are received and supported by the cable runs 86'. There is no interruption of incoming cartons during movements of the transporter and it is not necessary to reduce the speed of operation so that the transporter will move forward and back between delivery of the last carton of the stack being transported and the first carton of the next stack.

When and as the transporter reaches its rear stacking position the cartons on the cable runs 86' are dropped onto the supports 28 for the forming of a stack.

The shaft 70 and drum 76 may be rotated in opposite directions by various means but the following has been found to be adequate.

An associated reversible electric motor 89 and housing 92 containing gearing has a shaft 94 to which is fixed a crank disc 96. A member 98 is pivotally connected at 100 to the disc 96 and is provided with a longitudinal slot 102 slideable on a block 104 pivoted on shaft 70.

As the motor is operated the drum 76 is rotated to move the transporter between its stacking and non-stacking positions. The operation of the motor or other means for operating the cable drum may be controlled by any suitable means to facilitate producing stacks of the desired count.

In the form of the invention disclosed, the cartons which in stacked relation are transported to discharge position forwardly or in alignment with the direction of their movement into the apparatus may as well be transported at an angle relative to their direction of movement into the apparatus.

It will be noted that successive cartons are delivered to the apparatus and formed into a stack by means of the guides 32, side walls 42 and stop plate 54 and while the stack is moved to discharge position and the transporter is returning to stacking position the flow of incoming cartons is not interrupted.

The invention may be embodied in other specific forms without departing from the essential characteristics thereof. Hence, the present embodiments are therefore to be considered in all respects merely as being illustrative and not as being restrictive, the scope of the invention being indicated by the appended claims rather than by the foregoing description, and all modifications and variations as fall within the meaning and purview and range of equivalency of the appended claims are therefore intended to be embraced therein.

What it is desired to claim and secure by Letters Patent of the United States is:

1. Apparatus for stacking articles and trans-

porting stacks thereof comprising in combination, a support for a stack of articles, guiding means for receiving successive articles arranged whereby said articles descend to stacked position on said support, a movable transporter to transport successive stacks from stacking to discharge position, means to move said transporter, and other support means cooperating with said guiding means to support successive articles in stacking position while said transporter is moving between stacking and discharge positions adapted to release said articles onto said support when the transporter is in stacking position, said other support including flexible cables extending rearwardly from upper ends of said pusher members.

2. Apparatus for stacking successive articles and for transporting successive stacks to discharge position comprising in combination, a support, spaced side walls mounted thereon for movements to relatively adjusted positions, an upwardly extending rear guide between said side walls and a stop plate adjustable on one of said side walls and between said side walls, said side walls, guide and plate cooperating to receive and guide successive articles to a stacking position, a longitudinal supporting means for receiving successive articles, longitudinal ways, a transporter movable on said ways between stacking and discharge positions for transporting successive stacks and including pushers extending upwardly from said transporter for engaging and pushing said stacks, operating means including runs of flexible cable extending rearwardly from upper ends of said pushers adapted when said transporter is moving between stacking and discharge positions to support successive articles and to release them into stacking position when the transporter is in stacking position.

3. Apparatus for stacking successive articles and transporting successive stacks from stacking to discharge positions comprising in combination, a supporting structure, spaced longitudinal members secured to said supporting structure for supporting articles in stacked relation, rear and forward guides and side plates carried by said supporting structure for receiving and guiding successive articles into stacked relation, spaced longitudinal guideways carried by said supporting structure, a transporter slideable back and forth on said guideways between rear stacking and forward discharge positions having spaced upwardly extending pushers for moving a stack of articles from stacking to discharge position, means for moving said transporter including a drum rotatable in opposite directions and a pair of flexible cables in operative engagement therewith having opposite ends secured to said transporter and extending over wheels rotatable on said support, end portions of said cables extending rearwardly from upper ends of said pushers adapted to support successive articles when the transporter is in a position forwardly of said stacking position.
